Assistant Examiner — Sean D Lough

CLAIM

The ornamental design for the hexagonal translucent mesh light source container, as shown and described.

DESCRIPTION

FIG. 1 is a front side perspective view of the hexagonal translucent mesh light source container;

FIG. 2 is a front side view of the hexagonal translucent mesh light source container;

FIG. 3 is a back side view of the hexagonal translucent mesh light source container;

FIG. 4 is a top side view of the hexagonal translucent mesh light source container;

FIG. 5 is a bottom side view of hexagonal translucent mesh light source container;

FIG. 6 is a left side view of the hexagonal translucent mesh light source container; and,

FIG. 7 is a right side view of the hexagonal translucent mesh light source container.
